UNITED STATES PATENT OFFICE.

XAVIER J. JOLLER, OF OCONOMOWOC, WISCONSIN.

MUSIC-LEAF TURNER.

1,095,877.

Specification of Letters Patent.

Patented May 5, 1914.

Application filed December 4, 1912. Serial No. 734,962.

To all whom it may concern:

Be it known that I, XAVIER J. JOLLER, a citizen of the United States, residing at Oconomowoc, in the county of Waukesha and State of Wisconsin, have invented new and useful Improvements in Music-Leaf Turners, of which the following is a specification.

The invention relates to a music leaf turner.

10 The primary object of the invention is the provision of a device of this character wherein the sheets of music may be successively turned on manipulating a handle or lever of the device so that the player will 15 have the freedom of his hands when playing the piano or other instrument.

Another object of the invention is the provision of a music leaf turner wherein the music may be held therein when not in use 20 and on the playing of the piano the operator through the instrumentality of the device can successively turn the sheets of music without requiring the handling of the music while playing the piano or other instrument.

25 A further object of the invention is the provision of a music leaf turner wherein the lever for operating the same may readily be adjusted for the convenience of the 30 player of the piano or other instrument.

A still further object of the invention is the provision of a music leaf turner which is simple in construction, capable of being mounted upon a piano or other instrument 35 to be played, thoroughly reliable and efficient in operation and also inexpensive in manufacture.

With these and other objects in view the 40 invention consists in the construction, combination and arrangement of parts as will be hereinafter more fully described, illustrated in the accompanying drawings and pointed out in the claim hereunto appended.

In the drawings, Figure 1 is a front elevation of the piano showing the music leaf turner constructed in accordance with the 45 invention mounted thereon. Fig. 2 is a top plan view of the music leaf turner showing the cover removed. Fig. 3 is a vertical longitudinal sectional view through the device. Fig. 4 is a sectional view on the line 4—4 of Fig. 1. Fig. 5 is a vertical transverse 50 sectional view through the device. Fig. 6 is a sectional view on line 6—6 of Fig. 1. Fig. 55 7 is a perspective view of the slide. Fig. 8 is a vertical longitudinal sectional view through the adjustable racks.

Similar reference characters indicate corresponding parts throughout the several views of the drawings.

60

Referring to the drawings by numeral 10 designates generally a piano which is of the ordinary well-known construction and is merely shown to illustrate the mounting and manner of operation of the music leaf 65 turner, it being understood of course that the latter may be mounted upon any other instrument.

The music leaf turner comprises a box-like body 11 having a hinged top 12 and hinged 70 end doors 13 whereby access may be had to the interior of the body. In one end of the body 11 is formed a series of pigeon holes 14 adapted to receive music sheets or books, the door 13 being provided with any suitable 75 form of latch 15 so that the same may be fastened in closed position, while in the opposite end of the body 11 is mounted a transverse suspension rod 16 on which are detachably supported hangers 17 each being 80 designed to engage the upper edge of a music sheet for the hanging of the same within the body 11 of the device. The body 11 at its front is formed with a transparent 85 panel 18 although in lieu of this panel an ornamental plate may be positioned at the front of the said body to give attractiveness and neat appearance to the device.

Adapted to rest upon the bottom of the body 11 interiorly thereof is a base 19 from 90 the front edge of which rises a vertical plate 20 supporting a housing 21 in which is arranged the leaf turner mechanism presently described.

The leaf turning mechanism comprises a 95 series of vertically arranged turning shafts 22, 23, 24 and 25 respectively, the same being journaled in bearings 26 suitably fixed to the vertical plate 20 so that the said shafts will be held in vertical spaced relation to each other. 100 Extending outwardly at right angles from the upper end of the shafts are music sheet supporting arms 27 carrying suitable clips 28 for the fastening of the music sheet thereto, the front 18 of the body 11 being of less 105 height than the back and ends thereof so as to provide a space to allow the arms 27 free movement whereby they may swing in an arc forwardly of the said front 18 for the turning of the music sheets suspended therefrom. Formed in opposite sides of the housing 21 on the vertical plate 20 are guide 110 openings 29 in which works a slide 30 formed with tooth racks 31, 32, 33 and 34 respec-

tively, the racks 31, 32 and 33 being arranged in different planes with respect to each other while the rack 34 is located in the plane with the rack 31 and are adapted to successively mesh with their respective gears 35 fixed to the shafts 22, 23, 24 and 25, the said gears 35 being disposed in alinement with the said tooth racks so that on the shifting of the slide 30 in one direction the said tooth racks 10 will operate the respective gears 35 in successive order for the turning of the shafts in successive order thereby swinging the arms for the turning of the music sheet suspended therefrom.

15 Fixed to and projecting outwardly from the slide 30 is a handle 36 the same working in an elongated slot 37 formed in the front 18 of the body 11 and this handle is designed to permit the hand manipulation of 20 the slide for the turning of the music sheet supporting arms. Projecting laterally from opposite sides of the slide 30 are arms 38 and 39 respectively each being formed with an eye 40 and to these eyes are connected the 25 coil springs 41 the same being also connected with flexible pull cords 42 and 43 respectively which are trained through suitable guides 44 which are detachably connected to the piano 10 at opposite ends thereof, the 30 cord being operated in the manner presently described.

It is to be understood, of course, that the body 11 is mounted upon the music rack 45 or upon the top of the piano at the option 35 of the user while attached to the key board 46 on the said piano 10 is a guide 47 in which is arranged a slidable tooth rack 48, the guide 47 being formed with a clamp 49 carrying the usual set screw 50 whereby said 40 guide can be detachably clamped to the key board 46 of the piano. Disposed below the toothed rack 48 is an adjustable toothed rack 51, the teeth of both racks being designed to mesh with each other so that the said rack 45 51 can be shifted with relation to the rack 48, and this rack 51 is formed with an arm 52 which depends therefrom so as to project beneath the keyboard 46 of the piano, whereby the knee of the operator can be brought into 50 engagement with the arm 52 for the shifting of the rack 48, and in this manner pull upon either of the cords 42 and 43 for the actuation of the music leaf turner. The adjustable rack 51 has connected thereto at opposite 55 sides retractile springs 53 which are also connected with the toothed rack 48, and by pulling downwardly upon the lever 52 the said rack 51 can be pulled away from the rack 48 for disengaging the teeth of the respective racks from each other and thereby 60 permitting the hand adjustment of the rack 51 with relation to the rack 48 to suit the

convenient manipulation of the arm by the operator, that is to say, by placing the arm 52 at the proper point beneath the keyboard of the piano so as to be readily actuated. When the knee of the operator is pressed against the arm at one side thereof it will shift the toothed rack 48 in one direction, thereby causing the slide 30 to be moved 65 longitudinally within the case so as to bring the rack 34 into mesh with the pinion 35 on the shaft 25 and causing it to turn, thus turning the first sheet of the music, and when this rack runs out of mesh with the 70 said pinion the rack 30 will engage the pinion on the shaft 24, thus turning the same, and thereafter the rack 32 will mesh with the pinion on the shaft 23 next turning it, and finally the rack 31 will mesh with the 75 pinion on the shaft 22 causing it to turn the last sheet of music. The springs 41 are designed to give the necessary tension on the cords 42 and 43 for effecting the initial movement of the slide 30 without causing 80 the jerking thereof.

It will be evident that on manipulating the handle 36 the arms 27 can be swung successively in one direction for the turning of the music leaf. Should it be desired by the 90 operator to manipulate the slide 30 by hand it is only necessary to grip the lever 36 by one hand and shift the same in the required direction for the successive turning of the arms and the sheet music attached thereto. 95

From the foregoing it is thought that the construction and operation of the invention will be clearly understood and therefore more extended explanation has been omitted.

What is claimed is:—

A music leaf turner comprising a plurality of vertically arranged shafts, music leaf supporting arms projecting from said shafts, gears fixed to the shafts, a sliding member for actuating the same, extensions 105 at opposite ends of said member, flexible connections engaged with said extensions, a bracket adapted for detachable connection with a piano and formed with a guideway, a rack member slidable in the guideway and 110 engaged with the flexible connections, a toothed block adjustably connected with the rack member, a lever fixed in the said block and depending therefrom, and spring members connected with the block and rack member for holding the said block in adjusted engagement with the rack member. 115

In testimony whereof I affix my signature in presence of two witnesses.

XAVIER J. JOLLER.
